UNITED STATES PATENT OFFICE.

CARL HEINRICH THIEL, OF FREIBERG, GERMANY.

DESIGN FOR A LIQUEUR-BOTTLE.

43,248.

Specification for Design.

Patented Nov. 12, 1912.

Application filed August 1, 1912. Serial No. 712,792. Term of patent 3½ years.

To all whom it may concern:

Be it known that I, CARL HEINRICH THIEL, a subject of the King of Saxony, residing at Freiberg, Saxony, Germany, have invented a new, original, and ornamental Design for Liqueur-Bottles, of which the following is a specification, reference being had to the accompanying drawing, forming part thereof.

The figure is a front perspective view of a liqueur bottle, showing my new design.

It consists of a bottle in the form of an angel holding one pipe-head in each hand which may serve as a holder for candles and the like.

I claim:

The ornamental design for a liqueur bottle, as shown and described.

CARL HEINRICH THIEL. [L. S.]
